UNITED STATES PATENT OFFICE

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN

CARBURETOR FOR INTERNAL-COMBUSTION ENGINES

Application filed September 19, 1925. Serial No. 57,259.

This invention relates to internal combustion engines, and particularly to the carburetor mechanism thereof.

In the use of internal combustion engines in airplanes, it is desirable that the carburetor mechanism should operate efficiently at various inclinations of the plane or engine. The conventional float chamber mechanism of a carburetor operates well enough at slight inclinations, but there is usually no provision for operating as efficiently at steeper inclination or in an inverted position for any length of time.

It is one of the objects of the present invention that a carburetor mechanism be provided that will operate as efficiently on a steep climb or a steep descent as on a level.

Another object of the invention is to provide a carburetor mechanism that will operate efficiently in an airplane steeply banked on one side or the other.

Another object of the invention is to provide a carburetor mechanism that will maintain its level in an inverted position as well as in a normal position.

Another object of the invention is to provide a simple and efficient float mechanism for a carburetor for airplane engines or for other use.

Other objects of the invention will appear from the following description taken in connection with the drawings, which form a part of this specification, and in which:

Fig. 1 is a vertical section through a carburetor embodying the invention.

Fig. 2 is a slightly enlarged vertical section on line 2-2 of Fig. 1.

Fig. 3 is an enlarged perspective view of the float guiding means, and

Fig. 4 is another perspective view of the guide for the float.

Referring to the drawings, 10 represents the intake pipe of an internal combustion engine, and 11 is the usual butterfly throttle valve therein. 12 is a lower continuation of the intake pipe and forms the mixing chamber of the carburetor of this invention.

In the mixing chamber 12 is a Venturi tube 13 connected to the main air intake pipe 14

of the carburetor, and 15 is a choke valve in the latter pipe.

Extending into the Venturi tube 13 is the fuel nozzle 16 of the carburetor, the upper end 17 of which fuel nozzle is arranged in the more contracted part of the Venturi tube 13.

The float chamber mechanism of the carburetor is indicated generally by the numeral 18, and it will be noted instead of mounting this chamber low down on the carburetor, it is supported at a point just a little below the outlet or upper end 17 of the nozzle 16. Thus the float chamber mechanism 18 has an outlet 19 which is connected through a conduit 20 with the lower end of the fuel nozzle 16, so that the float chamber mechanism may supply liquid fuel to said nozzle.

The float chamber mechanism, as shown herein, comprises a substantially cylindrical float chamber 21, the axis of which is in its outlet 19, and the chamber is supported on the side of the carburetor body as by the connection 22.

The inlet 23 of the float chamber is, also, substantially on the axis of the chamber, and a pipe 24 supplies the inlet with liquid fuel from a higher lever than the chamber, or otherwise under pressure.

The inlet 23 and outlet 19, besides being arranged on the axis of the float chamber, are also extended inwardly toward the center of the chamber in the form of tubes 25 and 26 respectively.

The inlet 23 is controlled by a valve 27 having a spring 28 which tends to keep it open, and the valve is controlled by a float 29 arranged in the chamber and provided with a device 30 having a cam surface 31 which operates against the head of the valve 27. The float 29 is preferably of horseshoe-shape, as shown particularly in Figs. 1 and 2, and the part, or device 30, is connected to it so that it depends on the inner part of the horseshoe. This horseshoe-shape permits the float to partly surround the inlet and outlet tubes 25 and 26, and to turn relative to those tubes and always maintain an upright position in the chamber.

The float is guided in its movements by a guide member 32 having a shank 33 extending

into the outlet tube 26. The guide 32 has flanges 34 between which the device 30 of the float operates. Thus, as the float moves up, it carries with it the device 30, and the cam surface 31 operates against the valve 27 to close the latter. As the float moves down, the valve 27 will be opened by the spring 28. If the float chamber is moved around its axis, the float will stay in an upright position, and the 5 guide 32 will oscillate relative to the outlet tube 26. In order that the guide may not interfere with the outlet, its shank 33 is hollow and is provided with a slot 35 which registers with several openings or notches 36 in the 10 inner end of the tube 26.

From the above description, it will be seen that the float chamber 21 may be turned about its axis into any position, even in an inverted position, and the float 29 will still operate perfectly to control the level of liquid therein. The float chamber may, also, be tilted to one side or the other to a limited degree, and the float will still operate efficiently because of the arrangement of the inlet and outlet 15 adjacent to its central part.

It has been found unnecessary to provide a vent in the float chamber 21 if the usual three or four pounds of fuel pressure is supplied to the pipe 24, but if a lower pressure is 20 to be used, it may be desirable to make a very small vent in the normally upper part of the float chamber.

While I have herein described in some detail a specific embodiment of my invention, 25 which I deem to be new and advantageous and may specifically claim, I do not desire it to be understood that my invention is limited to the exact details of the construction, as it will be apparent that changes may be made therein 30 without departing from the spirit or scope of my invention.

Having thus described my invention, what I claim and desire to secure by Letters Patent is:

45 1. A carburetor float mechanism comprising a chamber having an inlet and an outlet, a valve for the inlet, and a vertically rotatable float for controlling said valve.

50 2. A carburetor float mechanism comprising a chamber having an inlet and an outlet, a float in said chamber, a valve for said inlet, and means connected to said float and arranged in said outlet for controlling said valve.

55 3. A carburetor float mechanism comprising a float chamber having an inlet and an outlet arranged adjacent the center of the chamber, a valve for the inlet, and a float in the chamber for controlling said valve.

60 4. A carburetor float mechanism comprising a float chamber having an inlet and an outlet arranged adjacent the center of the chamber, a valve for the inlet, and a horseshoe-shaped float in the chamber for controlling said valve.

5. In a carburetor, a float chamber, a valve for the inlet thereto, a float in said chamber for controlling said valve, and a pivoted guide for said float.

6. In a carburetor, a float chamber, a valve for the inlet thereto, a float in said chamber for controlling said valve, and a guide for said float adapted to rock with the various inclinations of the carburetor.

7. A carburetor float mechanism comprising a horseshoe-shaped float, a valve actuating cam operated by said float, and a pivoted guide for said cam.

8. In a carburetor float mechanism, the combination of a substantially cylindrical chamber, a float in said chamber, and a guide for said float pivotally supported substantially on the axis of the chamber.

9. In a carburetor float mechanism, the combination of a horizontally disposed substantially cylindrical chamber having an inlet substantially in the axis thereof, a float in said chamber and a valve for said inlet controlled by said float.

10. A carburetor float mechanism comprising a substantially cylindrical float chamber having its inlet and its outlet adjacent the axis of the chamber, a valve for the inlet, a float to control said valve, and a guide for said float pivotally supported adjacent the axis of said chamber.

11. A carburetor float mechanism comprising a chamber having its inlet and its outlet adjacent the center of the chamber, a valve for the inlet, a guide pivoted in the outlet, and a float in the chamber moving in said guide and controlling said valve.

12. A carburetor float mechanism comprising a horizontally disposed substantially cylindrical float chamber, and float operated means in said chamber for controlling the liquid level therein, said means being constructed to operate to maintain said level regardless of the position of said chamber about the axis of said chamber.

13. A carburetor float mechanism comprising a chamber, an inlet tube extending from one side of said chamber towards the center thereof, an outlet tube extending from adjacent the center of said chamber, a valve for said inlet tube, a guide mounted to oscillate in said outlet tube, a float in said chamber and a device on said float operating in said guide and having a cam surface for controlling said valve.

In testimony whereof I affix my signature.
LIONEL M. WOOLSON.
